COMBINATION ICE PICK

Charles Lorber, Louisville, Ky.

Application May 2, 1931. Serial No. 534,659

2 Claims. (Cl. 83—62)

This invention relates to combination tools and has special reference to the combination of an ice pick having a reciprocating handle and a second tool such as a bottle opener or ice breaker arranged to act as a striker for the ice pick.

One important object of the invention is to provide an improved general construction of devices of this character.

A second important object of the invention is to provide a novel device of this character of very simple construction and which may be economically manufactured.

With the above and other objects in view as will be hereinafter apparent, the invention consists in general of certain novel details of construction and combinations of parts hereinafter fully described, illustrated in the accompanying drawing and specifically claimed.

In the accompanying drawing like characters 20 of reference indicate like parts in the several views, and:

Figure 1 is a view of a form of the invention embodying an ice pick and bottle opener, the handle being shown in section.

Figure 2 is an elevation of the partly formed blank for the bottle opener in this form of the invention.

Figure 3 is a view of the upper part of a modified form embodying an ice pick and ice crusher, the handle being in section.

Figure 4 is a view similar to Figure 3 but showing a slight modification.

Figure 5 is an elevation of the form shown in Figure 4, the upper part only being shown.

In the form of the invention shown in Figures 1 and 2 there is provided a handle 10 preferrably of wood and this handle has a bore 11 extending inwardly from one end axially of the handle. This bore 10 terminates in spaced relation to the remaining end of the handle but a relatively small bore 12 extends through this end from the first bore. The open end of the bore 10 is closed by a metal cap or ferrule 13 having a central aperture wherethrough slides the shank 14 of an ice pick member having a sharp point 15 and provided within the bore with a collar 16 which limits the movement of the pick outwardly from the handle. This collar is located in spaced relation to the end of the shank 14 and forms a seat for one end of a spring 17 which surrounds the shank. Through the small bore 12 extends the shank end 18 of a metallic rod having a head 19 formed on the end. This head 19 lies within the bore 11 and rests on the shoulder formed between the two bores 11 and

12. This head substantially fills this part of the bore 11 and forms a seat for the upper end of the spring 17 and also constitutes a striker for the pick. The projecting end of the rod is bent to form a bottle cap removing loop 20 and is stamped to provide bottle cap engaging lugs 21.

In the form shown in Figure 3 the handle and pick are like the first form but the bottle cap opener is replaced by an oblatly spherical cap 22 having a shank 23 secured thereto and this shank passes through the small bore 12 and is provided within the bore 11 with a head 24 similar in shape and function to the head 19.

In the form shown in Figures 4 and 5 the upper end of the handle 25 is enlarged to form a spherical knob 26 and the handle is provided with an axial bore 27 of uniform diameter throughout and extending entirely through the handle. The knob 26 is covered by a spherical metal cap 28 which fits closely on the knob and closes the upper end of the bore 27 and also forms the striker for the shank 29 of the usual form of ice pick urged outwardly by a spring 30.

In the last two forms the metal cap is used as a hammer for crushing ice.

It is to be observed that in each case the ice pick forms a tool having a reciprocating hammering handle and that the other tool forms a striker for the pick.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In an ice pick, the combination of a tool handle having a bore extending inwardly from one end and terminating in spaced relation to the other end, said handle having a relatively small bore extending from the first bore through the last mentioned end and forming a shoulder at its junction with the first bore, a pin shank extending through said small bore and having a head on its inner end resting on the shoulder, a tool member reciprocable in said handle, a collar on said tool member spaced from the end adjacent said head, a spring surrounding said end of the tool member and bearing at one end against the head and at its other end against

the collar said head forming a striker for the tool member, and a head fixed on the outer end of said pin and holding the head on the pin against said shoulder.

- 5 2. In an ice pick, the combination of a tool handle having a bore extending inwardly from one end and terminating in spaced relation to the other end, said handle having a relatively small bore extending from the first bore through 10 the last mentioned end and forming a shoulder at its junction with the first bore, a pin shank extending through said small bore and having

a head on its inner end resting on the shoulder, a tool member reciprocable in said handle, a collar on said tool member spaced from the end adjacent said head, a spring surrounding said end of the tool member and bearing at one end against the head and at its other end against the collar said head forming a striker for the tool member, and a cap fitting over the handle and fixed to said shank and holding the head against the shoulder.
